(57) **CLAIM**

The ornamental design for an infusion pump, substantially as
shown and described.

DESCRIPTION

FIG. 1 is a perspective view of an infusion pump in accordance
with our design.

FIG. 2 is a bottom view of the infusion pump of FIG. 1.

FIG. 3 is a top view of the infusion pump of FIG. 1.

FIG. 4 is a right side view of the infusion pump of FIG. 1.

FIG. 5 is a left side view of the infusion pump of FIG. 1.

FIG. 6 is a front view of the infusion pump of FIG. 1; and,

FIG. 7 is a rear view of the infusion pump of FIG. 1.

The broken lines immediately adjacent the shaded areas
represent the bounds of the claimed design while all other broken
lines are directed to environment and are for illustrative pur-
poses only. The broken lines form no part of the claimed
design.
